BOTTLE CAP

Joseph B. Biederman, Cincinnati, Ohio

Application May 28, 1954, Serial No. 30,740

Term of patent 14 years

(Cl. D58—26)

Fig. 5.

Fig. 1.

Fig. 2.

Fig. 3.

Fig. 4.

Fig. 6.

Fig. 1 is a perspective view of a bottle cap embodying my new design;

Fig. 2 is a view in front elevation of the design shown in Fig. 1;

Fig. 3 is a view in side elevation thereof;

Fig. 4 is a bottom plan view thereof;

Fig. 5 is a top plan view thereof; and

Fig. 6 is a view in section taken on the line VI—VI in Fig. 2.

I claim:

The ornamental design for a bottle cap, as shown.
